FELT TIP PEN

Noboru Wakai, Tokyo, Katutoshi Ono, Kawasaki, and
Masatoshi Adachi, Tokyo, Japan, assignors to Pentel
Kabushiki Kaisha

Filed Dec. 28, 1970, Ser. No. 26,652

Claims priority, application Japan June 24, 1970

Term of patent 14 years

Int. Cl. D19—06

U.S. Cl. D74—17 B

Fig. 1

Fig. 2

Fig. 3

Fig. 4

Fig. 5

Fig. 6

FIG. 1 is a side elevational view of a felt tip pen showing our new design;

FIG. 2 is a front elevational view thereof;

FIG. 3 is a rear elevational view;

FIG. 4 is a side elevational view as it appears with the cap removed therefrom;

FIG. 5 is an enlarged top plan view of FIG. 2; and

FIG. 6 is an enlarged bottom plan view of FIG. 3.

We claim:

The ornamental design for a felt tip pen, substantially as shown.
